[57] CLAIM

The ornamental design for a pouch for a bottle, as shown and described.

DESCRIPTION

FIG. 1 is a top, left, perspective view of a pouch for a bottle showing my new design;

FIG. 2 is a front elevational view thereof;

FIG. 3 is a rear elevational view thereof;

FIG. 4 is a right side elevational view thereof; the left side being a mirror image of FIG. 4;

FIG. 5 is a bottom plan view thereof;

FIG. 6 is a top plan view thereof showing the top strap closed; and,

FIG. 7 is a top plan view thereof showing the configuration of the pouch for a bottle without the top strap.

The broken line depiction of a bottle in FIG. 1 is for illustrative purposes only and forms no part of the claimed design.
